UNITED STATES PATENT OFFICE.

JOHN HAGEL, OF GOLDFIELD, NEVADA.

ROTARY ENGINE.

1,301,689.

Specification of Letters Patent. Patented Apr. 22, 1919.

Application filed July 12, 1917. Serial No. 180,151.

To all whom it may concern:

Be it known that I, JOHN HAGEL, a citizen of the United States, and resident of Goldfield, in the county of Esmeralda and State 5 of Nevada, have invented certain new and useful Improvements in Rotary Engines, of which the following is a specification.

The present invention relates to improvements in engines; the dominant object of the 10 invention being to provide a rotary engine receiving its driving power from either combustible gas or steam, which, due to the absence of intricate valve operating mechanism, abutments, etc., will produce its maximum speed and power with but a minimum 15 amount of fuel.

Another object of the invention is to provide the engine with an improved form of piston, the same being light, compact and 20 capable of rotating without the loss of any of the force or power of the motive fluid.

Other objects of the invention are to provide novel intake valve operating mechanism, whereby the admittance of motive 25 fluid to rotor chamber will be properly timed; to provide yieldable packing for the piston or rotor to prevent loss of the motive power, and further, to provide means for effecting operation of the sliding abutment in 30 the rotor chamber at predetermined intervals.

Other independent objects are to provide features of construction of portions of the engine which tend toward the attainment of 35 the above aims irrespective of the relation in which they are used.

The invention accordingly consists of the features of construction, combination of elements and the arrangement of parts which 40 will be exemplified in the construction hereinafter set forth, and the scope of the application of which will be indicated in the following claims.

In the accompanying drawings, wherein is 45 shown one of various possible embodiments of my invention:—

Figure 1 is a vertical section through the improved engine;

Fig. 2 is a horizontal section therethrough;

50 Fig. 3 is a fragmentary transverse section in detail through the rotor chamber showing the yieldable piston packing;

Fig. 4 is a fragmentary detail in elevation of the intake valve operating means;

Fig. 5 is a similar view of the sliding 55 abutment operating means; and

Fig. 6 is a fragmentary detail in section showing the mounting of the sliding abutment in the rotor chamber.

Similar characters of reference refer to 60 similar parts throughout the several views of the drawings.

Having more particular reference to the drawings, 1 designates the base of my improved engine, which is formed upon the 65 lowermost portions of the several substantially L-shaped circular sections 2 and 3 which form the rotor chamber of the engine; these sections having marginal flanges 2' and 3' formed upon their adjacent ends 70 whereby bolts 4 or other suitable fastening devices may be passed therethrough for an obvious purpose. It is to be noted in this connection, that the arrangement of the sections 2 and 3 which constitute the rotor 75 chamber is such as to provide a circular slot or way upon the inner surface thereof.

Arranged concentrically of the rotor chamber of the engine is a power shaft 5, the opposite portions of which are rotatably supported in bearing pillars 6. A segment 7 having a bearing collar 8 formed thereon is keyed to the power shaft 5, as at 9, and has its outermost portion arranged adjacent the inner surface of the rotor chamber and is 85 movable over the slot or way formed therein.

Rotatable within the rotor chamber and arranged in the said slot or way formed therein is a circular band 10 substantially T-shaped in cross section and having apertured brackets 11 secured to its opposite ends, which brackets are connected by means of a bolt 12 carrying compression springs 13 on its opposite portions and in engagement with said brackets. A bridging piece 14 is 90 arranged over the jointure between the opposite ends of the circular band 10 and, obviously, serves to prevent the loss of motive power from the rotor chamber during operation of the engine. In this connection, it is 95 to be understood that the circular band 10 may be readily flexed and as a consequence, engagement of the same in the slot or way formed in the rotor chamber may be varied

by adjusting the tension of the springs 13 through the medium of the connecting bolt 12.

A piston or rotor 15 is mounted in the 5 rotor chamber and is provided with grooves or seats in which packing strips having interlocking ends as designated by the numeral 16 are arranged, compression springs 17 being arranged in suitable bores formed in the 10 piston and having bearing upon the said packing strips in order that close engagement between the same and the sides of the rotor chamber will be insured. Set screws 18 or like fastening devices are passed 15 through complementally arranged openings formed in the outermost portion of the segment 7 and the circular band 10 into engagement with screw threaded bores formed in the rotor 15 and serve as means for connecting 20 said elements and causing rotation of the same collectively.

Thickened portions 19 are arranged upon the sections 2 and 3 constituting the rotor chamber and are provided with a way 25 through which the sliding abutment 20 movable transversely of the rotor chamber passes. A hood 21 is arranged over the thickened portions 19 while strips 22 T-shaped in cross section are arranged upon 30 the opposite sides thereof and serve as means for closing the way through which the sliding abutment 20 travels; these strips 22 being secured in position through the medium of set screws 23. A stuffing gland 24 is 35 formed in the outer portion of the hood 21 and receives therethrough a stem 25 engaged with the slidable abutment 20, the stem in turn having an eye formed on its outer end in order that the same may be received between 40 the bifurcated portion of a lever 26 and pivotally connected thereto as at 27. As shown in Fig. 2, the remaining end of the lever 26 is pivotally engaged with a bracket arm 28 secured to the outer side of the rotor 45 chamber and having an opening formed intermediate its end, the purpose of which will be subsequently apparent. An operating rod 29 is slidably secured to one side of the rotor chamber in a bracket 30 and passes 50 through the opening in the bracket arm 28 into pivotal connection with the lever 26 through the medium of a link 31. The inner end of the rod 29 is bifurcated and has journaled therebetween a roller 32, which roller 55 is intermittently engaged by the cam 33 keyed onto the power shaft 5 of the engine.

In the opposite side of the rotor chamber there is formed an intake port, over which a valve casing 34 having a complemental port 60 therein is arranged and secured by set screws 35. An intake valve, preferably of the puppet type is arranged in the casing 34 and has the stem 36 thereof provided with a bifurcated portion 37 carrying a roller 38

therein. A cam 39 is keyed onto the adjacent portion of the power shaft 5 and as will be understood, intermittently engages the roller 38, thus, unseating the intake valve and allowing the admittance of motive fluid to the rotor chamber.

It may be here noted that should the improved rotary engine receive its power from combustible gas, a spark plug or other suitable form of ignition means may be arranged and extended into the rotor chamber. Further, it is to be also noted that the cam 33 which actuates the rod 29 is of such formation as to allow the holding of the sliding abutment in its retracted or inoperative position for a brief period of time in order that the rotor 15 may freely pass the same.

Formed within the peripheral surface of the rotor chamber and at the completion of the power stroke of the rotor 15 is an exhaust port 40, this port being at all times open in order that the rotor chamber may be thoroughly scavenged of the spent or exhausted motive fluid previous to the intake of a fresh charge.

Manifestly, the construction shown is capable of considerable modification and such modification as is within the scope of my claims, I consider within the spirit of my invention.

I claim:

1. In a rotary engine, a power shaft, a rotor chamber having an annular way formed in the inner surface thereof, a circular band T-shaped in cross section rotatable in said way, means for yieldably connecting the adjacent ends of the band, a rotor in said rotor chamber, a segment mounted on the power shaft and connected to the band and the rotor, an abutment slideable through said rotor chamber, an intake valve secured to one side and connected with the rotor chamber, an exhaust port in the rotor chamber, and means on said power shaft for actuating the abutment and intake valve at predetermined intervals.

2. In a rotary engine, a rotor chamber having inlet and outlet means communicating therewith and an annular way formed in the inner side thereof, a circular spring band having its opposite ends adjustably connected and being engaged in said annular way, a power shaft passing through the rotor chamber, a segment carried by said power shaft, a rotor connected to said segment and a portion of the annular band and arranged in the rotor chamber, and an abutment slideable in the rotor chamber and operable at pre-timed intervals.

3. In a rotary engine, a rotor chamber having inlet and outlet means communicating therewith, an annular way formed in the inner side of the chamber, a circular

spring band having its opposite ends adjustably connected and being engaged in said annular way, a power shaft arranged in the rotor chamber, a segment carried by said power shaft, a rotor arranged in the rotor chamber and connected to said segment and a portion of the circular band, spring pressed packing strips carried by said rotor engageable with the side walls of the rotor chamber, and a slidable abutment arranged in the rotor chamber adapted to be operated at pre-timed periods.

In testimony whereof, I affix my signature hereto.

JOHN HAGEL
